PNEUMATIC MEASURING DEVICE

Marcel Mennesson, Neuilly-sur-Seine, France, assignor to Societe Anonyme de Construction de Materiel Automobile S. A. C. M. A., Paris, France

Original application July 9, 1931, Serial No. 549,770. Divided and this application February 20, 1934, Serial No. 712,246. In Belgium September 9, 1930

4 Claims. (Cl. 33—178)

The present invention is a divided part of my co-pending application Serial No. 549,770 filed July 9, 1931, and relates to pneumatic measuring devices of the class described in the present inventor's co-pending applications, Serial No. 334,987, filed January 25, 1929 and Serial No. 442,915, filed April 9, 1930.

The object of the invention is to provide an apparatus for measuring the internal diameter or dimensions of a hollow tubular or cylindrical piece.

The accompanying drawing shows a diagrammatic section of one illustrative embodiment of the invention.

15 Referring to the figure, there is shown an assembly composed of the following elements; a chamber 1 provided with a needle valve controlling an air inlet port 2—a manometric tube 4² containing a liquid 4 and responding to variations 20 of pressure in chamber 1 via a conduit 4¹—an air supply tube 5 connected to a source of air pressure at 6,—a pair of tubes 7¹ and 7² intercalated between conduits 5 and 6 and extending into a liquid 8 to two different depths H and H¹.—25 a water supply conduit 9—an overflow 10—a conduit 12 communicating at one extremity via a port 11 with chamber 1 and at its opposite extremity with a bifurcated conduit 13—13¹. Discharge orifices 3 and 3¹ are situated at the extremities of the bifurcated conduit 13—13¹, formed inside an exploring element 22, to be introduced in the hollow cylinder C, whose internal diameter or dimensions are to be measured. The discharge orifices 3, 3¹, are guided to lie slightly 30 out of contact with internal walls of cylinder C, by projections 20—21 extending somewhat beyond said orifices. The exploring element 22 may be made in form of a circular disc for exploring object C when the latter is of cylindrical form.

40 The hereinabove described assembly operates in the following manner: Assuming water to be supplied via conduit 9 and discharged through overflow 10, air entering through conduit 6 will be fed at substantially constant pressure through 45 port 2 into chamber 1, momentary excess of pressure being eliminated by conduits 7¹ and 7² in a manner already described in the inventor's co-pending application Serial No. 334,987 filed January 25, 1929. Air is delivered from chamber 50 1 via port 11 to conduits 12, 13 and 13¹ and finds its way out through the pair of discharging orifices 3 and 3¹ adjacent the opposite walls of the cylinder C to be measured. Variations in the internal diameter of said cylinder C will change the 55 total discharge section adjacent orifices 3 and 3¹ and modify the reading in manometric branches

4¹ and 4² in a manner which will at once be evident.

It will be noted that the manometric readings are instantaneous and continuous during movement of exploring element 22 from point to point of cylinder C. It is not necessary to guide element 25 22 equidistantly from the opposite walls of cylinder C, the variations in pressure being additive and transmitted via conduit 12 to chamber 1.

What I claim is:—

1. An apparatus of the class described, comprising in combination, a source of fluid under substantially constant pressure, a chamber communicating with said source, conduit means including an exploring member having a branched 15 passage formed therethrough, the branches of the passage communicating with the atmosphere at the periphery of said exploring member, and means for measuring variation of pressure in said chamber, when said member is introduced between internal walls of an object, whereby variation 20 in the internal size of said object will be indicated by changes in indications of pressure in said chamber.

2. An apparatus of the class described, comprising in combination, a source of fluid under substantially constant pressure, a chamber communicating with said source, conduit means including an exploring member having a pair of 25 opposed passages formed therethrough, said passages communicating with the atmosphere at the periphery of said exploring member, and means for measuring variation of pressure in said chamber, when said member is introduced between internal walls of an object, whereby variation 30 in the internal size of said object will be indicated by changes in indications of pressure in said chamber.

3. An apparatus of the class described, comprising in combination, a source of fluid under 35 substantially constant pressure, a chamber communicating with said source, conduit means including a disc having a pair of passages formed therethrough, said passages communicating with the atmosphere at the periphery of said disc, and means for measuring variation of pressure in said chamber, when said disc is introduced between internal opposite walls of an object, whereby variation 45 in the internal size of said object will be indicated by changes in indications of pressure in said chamber.

4. A structure as defined in claim 1 in combination with means operative to prevent contact of the peripheral extremities of said passages with a surface when placed adjacent thereto.

MARCEL MENNESSON.
